UNITED STATES PATENT OFFICE.

FRANK H. NICHOLSON, OF EDGEWOOD, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed March 9, 1920, Serial No. 364,511. Renewed July 27, 1926.

My invention relates to railway traffic controlling apparatus, and particularly to apparatus of the type comprising automatic brake application means on a vehicle, and 5 trackway devices co-operating therewith to cause an application of the brakes in the event of unsafe traffic conditions in advance. In apparatus of this character, particularly when installed in conjunction with block signals of the usual type arranged to indicate 10 "proceed," "caution," and "stop," it is desirable to provide means for applying the brakes and stopping the vehicle upon passing a signal which indicates "caution" if the 15 driver of the vehicle is incapacitated or inattentive, while such an application may be undesirable or unnecessary if the driver properly observes the caution signal and is competent to take such action as conditions 20 may require.

One object of my invention is the provision of means under the control of the driver of the vehicle which is effective, for a limited time interval only, to prevent an automatic 25 application of the brakes due to co-operation of the vehicle carried apparatus with a trackway device.

I will describe one form of apparatus embodying my invention, and will then point 30 out the novel features thereof in claims.

In the accompanying drawings, Fig. 1 is a diagrammatic view showing one form of trackway apparatus adapted for co-operation with vehicle-carried apparatus embodying 35 my invention. Fig. 2 is a diagrammatic view showing one form of vehicle-carried apparatus embodying my invention.

Similar reference characters refer to similar parts in each of the views.

40 Referring first to Fig. 1, the reference characters 1 and 1^a designate the track rails on a railway along which traffic normally moves in the direction indicated by the arrow. These rails are divided by insulated 45 joints 4 to form a plurality of successive blocks A—B, B—C, C—D, etc. Located adjacent the entrance end of each block is a roadside signal designated by the reference character S with an exponent corresponding 50 to the location. Each of these signals, as here shown, is of the semaphore type adapted to indicate "stop", "caution" and "proceed" according as the semaphore is in the hori-

zontal, the inclined, or the vertical position. The apparatus for controlling these signals is omitted from the drawing for the reason 55 that it forms no part of the present invention, but it is understood that in accordance with usual practice each signal indicates "stop" when the corresponding block is occupied, "caution" when the corresponding block is unoccupied and the block next 60 in advance is occupied, and "proceed" when the corresponding block and the block next in advance are unoccupied. Thus, as 65 shown in the drawing, the block to the right of point D is occupied by a vehicle V', so that signal S^D for this block indicates "stop", signal S^C indicates "caution", and signal S^B indicates "proceed." 70

Located adjacent the entrance end of each block is a trackway device designated by the reference character R with an exponent corresponding to the location. As here shown, each of these devices is in the form of a 75 ramp or contact rail. Each ramp R is provided with a trackway battery which is designated 2 with an exponent corresponding to the location. One terminal of each battery is connected with the lower track rail 1, 80 while the other terminal is at times connected with the adjacent ramp through the medium of a circuit controller which is designated 3 with an exponent corresponding to the location. Each circuit controller is 85 operated by the adjacent signal in such manner that the circuit controller is closed when the signal indicates "proceed", but open when the signal indicates "caution" or "stop". It will be seen, therefore, that 90 each ramp R is energized only when the corresponding block and the block next in advance are unoccupied.

Referring now to Fig. 2, the vehicle carried apparatus, in the form here shown, includes a brake application valve E controlled by a magnet M, which magnet is in turn governed by a circuit controller F operated by a contact shoe G. This contact shoe is arranged to be elevated by each trackway 100 ramp R, and when so elevated it opens circuit controller F.

The brake application valve E comprises a valve body 5 containing a slide valve 6 which controls the exhaust of air from a 105 pipe 7 leading to the brake pipe of the

vehicle braking system. When the slide valve is in the right hand position, as shown in the drawing, the pipe 7 is closed, but when the valve moves to the left this pipe 5 is opened to atmosphere through a chamber 9 and an exhaust port 8, so that an automatic application of the brakes then occurs. The slide valve 6 is actuated by a piston 10 operating in a cylinder 11, the piston 10 10 and valve 6 being biased to the right by a spring 13. Air from the main reservoir of the braking system is constantly supplied to the valve body 5, and so to the right hand face of piston 10, through a pipe 14, and 15 this air is also admitted to the left hand side of the piston through a small orifice 12 in the piston. It follows that when the left hand end of cylinder 11 is closed, the air pressures on opposite sides of piston 10 are 20 balanced so that this piston is held in its right hand position by the spring 13. The left hand end of cylinder 11 may be opened to atmosphere, however, by means of a valve 15 which in turn is controlled by the armature of magnet M. When the magnet is energized, this valve is closed, but when the magnet becomes de-energized the valve 15 opens, so that the left hand end of cylinder 11 is then opened to atmosphere through a 25 port 16 the area of which is greater than that of the piston port 12. When this occurs, the air pressure on the left-hand face of piston 10 is reduced sufficiently to permit the pressure on the right-hand face of the 30 piston to shift the piston and the slide valve 6 to their left-hand positions. This movement causes an automatic application of the brakes by connecting pipe 7 with atmosphere through exhaust port 8.

40 When the piston and slide valve are in brake applying positions the left-hand end of cylinder 11 is also connected with atmosphere through a pipe 17, valve chamber 18, pipe 19, and exhaust port 20, so that the 45 brakes will not be released by re-energization of magnet M alone. The brakes can only be released by manual operation of a plunger 21 which, when moved inwardly, disconnects pipe 19 from exhaust port 20 50 and so permits the pressure on the left-hand face of piston 10 to build up to such point that the piston moves to the right. The subsequent release of the plunger 21 has no effect because pipe 17 is then disconnected 55 from pipe 19.

The magnet M is normally energized by virtue of a vehicle-carried circuit which passes from a battery 22 through wire 28, circuit controller F, wires 23, 24 and 25, 60 winding of magnet M, wires 26 and 27 to battery 22. It will be seen that when the shoe G is elevated by a ramp R this circuit will be opened at circuit controller F, so that magnet M will then become de-energized unless other means are provided to

prevent such operation. If the circuit controller 3 at such ramp is closed, a second circuit for magnet M becomes closed which circuit is from the trackway battery 2, through circuit controller 3, ramp R, shoe 70 G, wires 29 and 25, winding of magnet M, wires 26 and 30 to the frame and wheels of the vehicle, thence through track rail 1 to battery 2. It follows, therefore, that when the vehicle passes a ramp R, the brakes 75 will be applied if the ramp is de-energized but not if it is energized.

It will be seen that with only the apparatus thus far described, it would be impossible for a vehicle to pass a de-energized ramp, that is, a caution or a stop signal, without incurring an automatic application of the brakes. This is undesirable, in the case of the stop signal under the circumstance that the vehicle is under control and 80 has been already brought to a stop before passing the stop signal. The necessity for avoiding undue delay demands that the vehicle be permitted to proceed past the signal and continue through the block, provided 85 the driver was fully cognizant of the stop signal. Furthermore, it is undesirable, in the case of the caution signal, under the condition that the driver observes the caution signal indication by taking such action as 90 to insure stopping his vehicle before passing the next signal. It is desirable to stop the vehicle automatically only in case the driver is inattentive or incapacitated, as may be made manifest by his failure to observe and 95 acknowledge signal indications. I, therefore, provide means for permitting the vehicle to pass a de-energized ramp without incurring an automatic application of the brakes, 100 under the condition that the driver of the vehicle takes suitable action in acknowledgement of the caution or stop signal. The means which I have provided for accomplishing this result is as follows:

The vehicle-carried circuit for magnet M 110 is provided with a shunt around the shoe-operated contact F, which shunt passes from battery 22 through wire 31, circuit controller H, and wire 32 to wire 24. It will be seen, therefore, that when circuit controller H is closed magnet M will remain energized upon the opening of circuit controller F by a ramp R, even though no current is received from the corresponding trackway battery 2.

Circuit controller H comprises a contact plate 37 which is attached to a piston rod 33, this piston rod being integral with a piston 33 operating in a cylinder 34. The piston is biased upwardly by a spring 35, so that when no other force acts on this piston circuit controller H is open. When air is admitted to the upper end of cylinder 34, however, piston 33 is driven downwardly, so that circuit controller H then becomes 125 130

closed. Air is at times supplied to the upper end of cylinder 34 from a timing reservoir K, and the supply of air to this reservoir and to the cylinder 34 is controlled by a valve L provided with a handle 36. When the valve L is in the position shown in the drawing, the timing reservoir K is connected with the main reservoir of the braking system through pipes 14 and 39. When 10 the handle 36 is moved upwardly, however, as indicated by the arrow, reservoir K is disconnected from the main reservoir and is connected with the upper end of cylinder 34 through pipes 39 and 40. Air then flows 15 from the timing reservoir into the upper end of the cylinder 34, so that piston 33 is moved downwardly, whereupon the air passes out to atmosphere through a port 38 of restricted area, so that circuit controller 20 H is closed for only a predetermined interval of time such, for example, as 20 seconds. At the end of this time interval the pressure on the upper surface of piston 33 is reduced to such value that this piston 25 turns to its uppermost position under the influence of spring 35, even though valve L is not returned to its normal position.

It follows from the foregoing that when a vehicle which is equipped with the apparatus shown in Fig. 2 approaches a caution signal, that is, a de-energized ramp R, the driver may pass such signal without incurring an automatic application of the brakes by swinging the valve handle 36 upwardly just before the shoe G engages the ramp R. Similarly, when approaching a stop signal the driver will bring the vehicle to a stop and he may then proceed past the signal by again swinging the valve handle 40 36 upwardly just before shoe G encounters ramp R. It will be observed that if the handle 36 is not returned to its initial position after passing a de-energized ramp an automatic application of the brakes will be 45 incurred when the vehicle reaches the next de-energized ramp.

Although I have herein shown and described only one form of apparatus embodying my invention, it is understood that various changes and modifications may be made therein within the scope of the appended claims without departing from the spirit and scope of my invention.

Having thus described my invention, 55 what I claim is:

1. Railway traffic controlling apparatus comprising normally inactive means carried on a vehicle for applying the brakes, trackway devices for co-operation with said means to cause an application of the brakes, and manually operable means on said vehicle for removing said brake applying means from control by said trackway devices for a given interval of time.

60 2. Railway traffic controlling apparatus

comprising a circuit on a vehicle including a normally closed contact, devices located at intervals in the trackway for opening said contact, manually operable means on the vehicle for closing a branch around said contact for a given interval of time to prevent the opening of said circuit by a trackway device, and means controlled by said circuit for causing a brake application when the circuit is open. 75

3. Railway traffic controlling apparatus comprising an electro responsive device on a vehicle, a vehicle carried circuit for said device including a source of current and a normally closed contact, devices located at intervals in the trackway for opening said contact, manually operable means on the vehicle for closing a branch around said contact for a given interval of time to prevent de-energization of said electro-responsive device by a trackway device, and means controlled by said electro-responsive device when de-energized for causing a brake application. 80

4. Railway traffic controlling apparatus comprising an electro responsive device on a vehicle, a vehicle carried circuit for said device including a source of current and a normally closed contact, devices located at intervals in the trackway for opening said contact and for supplying current to said electro responsive device independently of said vehicle carried circuit when traffic conditions ahead are safe but not when they are dangerous, manually operable means on the vehicle for closing a branch around said contact for a given interval of time to prevent de-energization of said electro responsive device by a trackway device when traffic conditions ahead are dangerous, and means controlled by said electro responsive device when de-energized for causing a brake application. 90 100

5. Railway traffic controlling apparatus comprising ramp rails located at intervals in the trackway and each arranged to be energized or de-energized according as traffic conditions in advance are safe or dangerous, a contact shoe carried by a vehicle and arranged to engage each ramp rail, apparatus 110 on the vehicle for applying the brakes when said shoe engages a de-energized ramp rail but not when it engages an energized rail, and manually operable means on the vehicle effective for a given interval of time 115 to prevent a brake application due to the engagement of said shoe with a de-energized ramp rail. 120

6. Railway traffic controlling apparatus comprising automatic brake application 125 mechanism on a vehicle, a reservoir on the vehicle normally connected with a source of fluid pressure, a cylinder, a piston therein biased to one position, manually operable means on the vehicle for disconnecting said 130

reservoir from said source and connecting the reservoir with said cylinder and with a small exhaust orifice whereby said piston is moved to another position for a given interval of time, and means for rendering said mechanism ineffective while said piston is in the latter position.

7. Railway traffic controlling apparatus comprising automatic brake application mechanism on a vehicle, a reservoir on the vehicle normally connected with a source of fluid pressure, manually operable means for disconnecting said reservoir from said source of pressure and connecting it with a small exhaust orifice, and apparatus for rendering said mechanism ineffective while the pressure in said reservoir is reducing due to operation of said manual means.

8. Railway traffic controlling apparatus comprising automatic brake application mechanism on a vehicle, a reservoir on the vehicle normally connected with a source of fluid pressure, manually operable means for disconnecting said reservoir from said source and connecting it with a pressure-responsive device and with a small exhaust orifice, and means for rendering said mechanism ineffective to apply the brakes while the pressure in said pressure-responsive device is above a given value.

9. Railway traffic controlling apparatus comprising normally inactive mechanism on a vehicle for applying the brakes, trackway devices arranged for co-operation with said mechanism to cause a brake application, a reservoir on the vehicle normally connected with a source of fluid pressure, manually operable means on the vehicle for disconnecting said reservoir from said source and connecting it with a pressure-responsive device and with a small exhaust orifice, and means effective while the pressure in said pressure-responsive device is above a given value to prevent a brake application due to co-operation of said mechanism with a trackway device.

10. Railway traffic controlling apparatus comprising a vehicle, a reservoir on the vehicle normally connected with a source of fluid pressure, a cylinder, a piston therein biased to one position, manually operable means on the vehicle for disconnecting said reservoir from said source and connecting said reservoir from said source and connecting the reservoir with said cylinder and with a small exhaust orifice whereby said piston is moved to another position for a given interval of time, and automatic traffic governing mechanism on said vehicle controlled by said piston.

11. Railway traffic controlling apparatus comprising a vehicle, a reservoir on the vehicle normally connected with a source of fluid pressure, manually operable means for disconnecting said reservoir from said source

of pressure and connecting it with a small exhaust orifice, and automatic traffic governing mechanism on said vehicle controlled by the pressure in said reservoir.

12. Railway traffic controlling apparatus comprising a vehicle, a reservoir on the vehicle normally connected with a source of fluid pressure, manually operable means for disconnecting said reservoir from said source and connecting it with a pressure-responsive device and with a small exhaust orifice, and automatic traffic governing mechanism on said vehicle controlled by said pressure-responsive device.

13. Railway traffic controlling apparatus comprising a vehicle, a normally charged fluid pressure reservoir thereon, means under the control of the engineer for discharging said reservoir through an orifice of restricted area, and automatic traffic governing mechanism on said vehicle controlled by the pressure in said reservoir.

14. A time element device for railway traffic controlling apparatus comprising a reservoir normally connected with a source of fluid pressure, a cylinder, a piston therein biased to one position, and manually operable means for disconnecting said reservoir from said source of fluid pressure and connecting the reservoir with said cylinder and with a small exhaust orifice whereby said piston is moved to another position for a given interval of time.

15. Railway traffic controlling apparatus comprising devices located at intervals in the trackway and each arranged to be energized or de-energized according as traffic conditions in advance are safe or dangerous, a receiver carried by a vehicle and arranged to co-act with each trackway device, apparatus on the vehicle for applying the brakes when said receiver co-acts with a de-energized trackway device but not when it co-acts with an energized device, and manually operable means on the vehicle effective for a given interval of time to prevent a brake application notwithstanding co-action of said receiver with a de-energized trackway device.

16. Railway traffic controlling apparatus comprising ramp rails located at intervals in the trackway and each arranged to be energized or de-energized according as traffic conditions in advance are safe or dangerous, a contact shoe carried by a vehicle and arranged to engage each ramp rail, apparatus on the vehicle for applying the brakes when said shoe engages a de-energized ramp rail but not when it engages an energized rail, and manually operable means on the vehicle effective for a given interval of time to prevent a brake application notwithstanding engagement of said shoe with a de-energized ramp rail.

17. Railway traffic controlling apparatus

comprising a series of devices located at intervals along the trackway, automatic brake applying apparatus on the train comprising a shoe and arranged to apply the brakes 5 when the shoe engages a trackway device, a normally charged fluid pressure reservoir on the vehicle, means under the control of the engineer for discharging said reservoir through an orifice of restricted area, and 10 means responsive to the pressure in said reservoir for preventing an automatic application of the brakes notwithstanding the engagement of said shoe with a trackway device.

15 18. Railway traffic controlling apparatus comprising a series of devices located at intervals along the trackway, automatic brake applying apparatus on the train comprising a shoe and arranged to apply the brakes 20 when the shoe engages a trackway device if traffic conditions in advance are dangerous but not if traffic conditions in advance are safe, a normally charged fluid pressure reservoir on the vehicle, means under the control 25 of the engineer for discharging said reservoir through an orifice of restricted area, and means responsive to the pressure in said reservoir for preventing an automatic application of the brakes notwithstanding the engagement of said shoe with a trackway device under dangerous traffic conditions.

19. Railway traffic controlling apparatus comprising a series of devices located at intervals along the trackway, mechanism on a 35 vehicle arranged to successively engage said devices, apparatus adapted to cause an automatic application of the brakes when said mechanism engages a trackway device under predetermined conditions, a normally charged fluid pressure reservoir on the 40 vehicle, means under the control of the engineer for discharging said reservoir through an orifice of restricted area, and means responsive to the pressure in said reservoir for 45 preventing an application of the brakes notwithstanding the engagement of said mechanism with a trackway device under such predetermined conditions.

20. Railway traffic controlling apparatus 50 comprising normally inactive vehicle carried brake applying means including a shoe, trackway devices for engaging said shoe to cause an application of the brakes, and manually operable means on the vehicle for removing said brake applying means from control by said trackway devices for a time 55 interval notwithstanding engagement of said shoe with a trackway device.

21. Railway traffic controlling apparatus 60 comprising a normally inactive air release valve carried on a vehicle for automatically applying the brakes when operated, trackway devices, and manually controlled mechanism including a hand lever on said vehicle 65 for eliminating the function of said air re-

lease valve, and for determining a duration of time that said elimination must remain in force to pass the trackway devices, said mechanism also including a pneumatically operable and automatically restorable part, 70 which, by its restoration terminates the said time interval, while said hand lever remains in its operated position.

22. Railway traffic controlling apparatus 75 comprising a series of devices located at intervals along the trackway, automatic brake applying apparatus on the train comprising a receiver and arranged to apply the brakes when the receiver co-acts with a trackway device, a normally charged fluid pressure reservoir on the vehicle, means under the control of the engineer for discharging said reservoir through an orifice of restricted area, and means responsive to the pressure in said reservoir for preventing 80 an automatic application of the brakes notwithstanding the engagement of said receiver with a trackway device.

23. Railway traffic controlling apparatus 85 comprising a series of devices located at intervals along the trackway, automatic brake applying apparatus on the train comprising a receiver and arranged to apply the brakes when the receiver co-acts with a trackway device if traffic conditions in advance are 90 dangerous but not if traffic conditions in advance are safe, a normally charged fluid pressure reservoir on the vehicle, means under the control of the engineer for discharging said reservoir through an orifice 95 of restricted area, and means responsive to the pressure in said reservoir for preventing an automatic application of the brakes notwithstanding the engagement of said receiver with a trackway device under dangerous traffic conditions.

24. Railway traffic controlling apparatus 100 comprising a series of devices located at intervals along the trackway, mechanism on a vehicle arranged to successively co-act 110 with said devices, apparatus adapted to cause an automatic application of the brakes when said mechanism co-acts with a trackway device under predetermined conditions, a normally charged fluid pressure reservoir on 115 the vehicle, means under the control of the engineer for discharging said reservoir through an orifice of restricted area, and means responsive to the pressure in said reservoir for preventing an application of the 120 brakes notwithstanding the co-action of said mechanism with a trackway device under such predetermined conditions.

25. In combination, a railway vehicle provided with a braking system, automatic apparatus on the vehicle for causing an automatic application of the brakes and for preventing release of the brakes after an automatic application has occurred until the vehicle has been brought to a full stop, devices 125 130

- located in the trackway for setting said automatic apparatus into operation, and manually operable means on the vehicle effective for a limited interval of time to prevent an automatic application of the brakes notwithstanding co-action of said apparatus with a trackway device.
26. In railway traffic controlling apparatus, a train carried device having a normal inactive condition, manually operable means on the vehicle for changing said device to an active condition, means for automatically restoring said device to its normal condition after a given time interval even if said manually operable means is held in its operated position, and governing apparatus on the train controlled in part by said device.
27. In railway traffic controlling apparatus, a train carried device having a normal inactive condition, manually operable means on the vehicle for changing said device to an active condition, means for automatically restoring said device to its normal condition after a given time interval even if said manually operable means is held in its operated position, apparatus on the train controlled from the trackway for causing an application of the brakes, and means for preventing such brake application while said device is in its active condition.
28. In railway traffic controlling apparatus, train carried manually operable member having a normal position and an operated position, a device having a normal inactive condition, means responsive to operation of said member for changing said device to an active condition and for restoring the device to its inactive condition after a given time interval even if said manually operable member is held in its operated position, and governing apparatus on the train controlled in part by said device.
29. In railway traffic controlling apparatus, a train carried manually operable member having a normal position and an operated position, a device having a normal inactive condition, means responsive to operation of said member for changing said device to an active condition and for restoring the device to its inactive condition after a given time interval even if said manually operable member is held in its operated position, apparatus on the train controlled from the trackway for causing an application of the brakes, and means for preventing such brake application while said device is in its active condition.
30. In railway traffic controlling apparatus, a train carried manually operable but automatically restorable device capable of being manually held in operated condition for only a given interval of time, and governing apparatus on the train controlled in part by said device.
31. In railway traffic controlling apparatus, a train carried device having a normal inactive condition and arranged to automatically return to said condition after a given time interval following a change to active condition, manually operable means for changing said device to its active condition but incapable of preventing return of said device to its inactive condition, and governing apparatus on the train controlled in part by said device.
32. In railway traffic controlling apparatus, a train carried device having a complete cycle of operation from an inactive condition to an active condition and back to inactive condition, manually operable means for initiating said cycle but incapable of preventing completion of said cycle, and governing apparatus on the train controlled in part by said device.
33. In railway traffic controlling apparatus, a train carried manually operable member having a normal position and an operated position, a normally open circuit controller, means responsive to operation of said member for closing said circuit controller and for again opening the circuit controller after a given time interval even if said member is held in its operated position, and governing apparatus on the train controlled in part by said circuit controller.
34. In railway traffic controlling apparatus, a train carried manually operable member having a normal position and an operated position, a normally open circuit controller, means responsive to operation of said member for closing said circuit controller and for again opening the circuit controller after a given time interval even if said member is held in its operated position, apparatus on the train controlled from the trackway for causing an application of the brakes, and means for preventing such brake application while said circuit controller is closed.

In testimony whereof I affix my signature.
FRANK H. NICHOLSON.
